UNITED STATES PATENT OFFICE

98,297

DESIGN FOR A DISPLAY RACK

Samuel C. Earley, Toledo, Ohio, assignor to The Acklin Stamping Company, Toledo, Ohio, a corporation of Ohio

Application May 20, 1935, Serial No. 56,914

Term of patent 7 years

To all whom it may concern:

Be it known that I, Samuel C. Earley, a citizen of the United States of America, residing at Toledo, in the county of Lucas and State of Ohio, have invented a new, original, and ornamental Design for Display Rack, of which the following is a specification, reference being had therein to the accompanying drawing, forming a part thereof, in which the figure is a perspective view of a display rack showing my design.

The dominant feature of my new design consists in the supporting of rows of articles to be displayed at different elevations and the association of the lamp box with the supporting means for the articles to be displayed.

I claim:

The ornamental design for a display rack substantially as shown and described.

SAMUEL C. EARLEY.
